(57) **CLAIM**

The ornamental design for a jacket with scalloped shoulder regions, as shown and described.

DESCRIPTION

FIG. 1 is a front perspective view of a first embodiment of a jacket with scalloped shoulder regions of the present design;

FIG. 2 is a front view of the first embodiment thereof;

FIG. 3 is a rear view of the first embodiment thereof;

FIG. 4 is a right side view of the first embodiment thereof;

FIG. 5 is a left side view of the first embodiment thereof;

FIG. 6 is a top view of the first embodiment thereof;

FIG. 7 is a bottom view of the first embodiment thereof;

FIG. 8 is a rear perspective view of the first embodiment thereof;

FIG. 9 is a front perspective view of a second embodiment of a jacket with scalloped shoulder regions of the present design;

FIG. 10 is a front view of the second embodiment thereof;

FIG. 11 is a rear view of the second embodiment thereof;

FIG. 12 is a right side view of the second embodiment thereof;

FIG. 13 is a left side view of the second embodiment thereof;

FIG. 14 is a top view of the second embodiment thereof;

FIG. 15 is a bottom view of the second embodiment thereof;

and,

FIG. 16 is a rear perspective view of the second embodiment thereof.
